CLAIM

The ornamental design for a cookware vessel lid, as shown and described.

DESCRIPTION

FIG. 1 is a perspective view from above and between the back and right sides of a first embodiment of a "cookware vessel lid" showing my new design;

FIG. 2 is a front elevational view of FIG. 1;

FIG. 3 is a back elevational view of FIG. 1;

FIG. 4 is a left side elevational view of FIG. 1;

FIG. 4 is a left side elevational view of FIG. 1;

FIG. 6 is a top plan view of FIG. 1.

The broken lines shown in FIGS. 1-6 are for illustrative purposes only and form no part of the claimed design.
